UNITED STATES PATENT OFFICE

137,509

DESIGN FOR A SHIRT

Jessie Byrd Bernhard, Birmingham, Ala.

Application June 25, 1943, Serial No. 110,521

Term of patent 14 years

(Cl. 3—25)

To all whom it may concern:

Be it known that I, Jessie Byrd Bernhard, a citizen of the United States, residing at Birmingham, in the county of Jefferson and State of Alabama, have invented a new, original, and ornamental Design for a Shirt, of which the following is a specification, reference being had to the accompanying drawing, forming a part thereof.

This application is a continuation in part of my previously filed application, Serial Number D-108,328, filed September 24, 1942.

In the drawing,

Fig. 1 is a front view of a shirt showing my new design, with the ascot in tied position;

Fig. 2 is a rear view thereof, and

Fig. 3 is a front view of the shirt shown in Fig. 1 with the top button unbuttoned and the ascot in untied position.

The characteristic feature of my design resides in the combination on the shirt disclosed of the specific lapels and attached ascot collar and tie of the proportions shown.

I claim:

The ornamental design for a shirt, substantially as shown and described.

JESSIE BYRD BERNHARD.
